MOUNTING AND OPERATING MECHANISM
FOR MUD GUNS

Edgar E. Brosius, Pittsburgh, Pa.

Application April 26, 1944, Serial No. 532,801

28 Claims. (Cl. 266—42)

This invention relates to mounting and operating mechanism for so-called mud guns for plugging holes with clay or the like, as, for example, the tapping holes of blast and other furnaces. The invention has to do with simplified and improved operating means for moving the gun carrier toward and from position in which the gun carried thereby may plug a hole and simplified and improved motive or power applying means for causing operation of the operating means for moving the gun carrier and for operating the mud gun itself.

Various motive or power applying means for operating mud guns and for moving mud guns toward and from operative position have been employed. Originally mud guns were "swung into the hole" by hand and the gun pistons were operated by steam or water supplied through flexible connections from a remote source. Later steam was used universally both for moving mud guns toward and from operative position and for operating the guns themselves. The use of steam has certain disadvantages which have long been recognized, primary among which are the inconvenience of piping steam from boilers to the guns and the fact that the steam pipes are in the way and constitute a nuisance, the difficulty of maintaining steam pressure and the hazards incident to the use of steam. Mechanical means operated by electric motors have been employed both for moving mud guns toward and from position and for operating the guns themselves. Hydraulic means including a fluid pressure system mounted on the gun itself have been proposed for gun operation but no hydraulic means including a local fluid pressure system has been employed for moving the gun into and out of operative position. Hydraulic means are in general the most satisfactory, but the difficulties incident to the supplying of hydraulic fluid from a pressure source and the application of hydraulic power in so-called gun swinging movements have not heretofore been overcome.

I have discovered how to overcome the difficulties above referred to incident to the use of hydraulic power for both moving a gun into and out of operative position and operating the gun itself to plug a hole. Advantage is taken of the flexibility of hydraulic power for performing both of these functions and danger of breakdowns due to failure of purely mechanical operating mechanism is avoided. I provide a self-contained mounting and operating mechanism for a mud gun in which the gun is moved toward and from operative position and also operated to plug a

hole by hydraulic or fluid pressure power created by a fluid pressure system forming an integral part of the mounting and operating mechanism. Steam pipes and flexible fluid connections from remote sources are entirely eliminated. The only operating connections from the mounting and operating mechanism to a remote point are wires leading from a single electric motor and two solenoid operated valves on the mounting and operating mechanism to a control panel located at any convenient more or less remote point.

I provide mounting and operating mechanism for a mud gun comprising a support, a gun carrier supported by and movable relatively to the support to dispose a mud gun carried by the carrier in operative position relatively to a hole to be plugged and to withdraw the gun therefrom, a fluid pressure system carried by the carrier and means including connections with the fluid pressure system for moving by the compressed fluid the carrier relatively to the support. I further provide such mounting and operating mechanism in which the compressed fluid also operates the mud gun to plug the hole.

25 I preferably provide a fluid reservoir carried by the gun carrier, fluid pump means carried by the carrier, connections between the reservoir and pump means providing for compression by the pump means of fluid from the reservoir and means operated by the compressed fluid for moving the carrier relatively to the support and desirably also operating the gun to plug the hole.

30 I further provide improved mechanical operating means for moving the gun carrier toward and from position in which the gun may plug a hole. I employ rack and pinion means for moving the gun carrier relatively to its support in moving the gun into and out of operative position. Such operating means not only operates the gun carrier in a very simple manner, obviating the necessity of employing complex and expensive mechanism, but it cooperates in a unique and highly desirable way with the fluid pressure motive means as the rack may be operated by a fluid driven piston, resulting in moving of the gun into and out of operative position simply by movement of a piston in a cylinder mounted on the carrier.

35 Preferably the gun carrier is turnable about its support to dispose the gun in operative position relatively to a hole to be plugged and to withdraw the gun therefrom and rack and pinion means are employed for turning the carrier about the support. The pinion may be mounted on the support, preferably fixedly, and the rack may be

connected with the carrier so as to be operated therefrom. The rack meshes with the pinion and operation of the rack causes turning or swinging of the gun carrier about the support.

As above stated, a fluid pressure system is preferably mounted on the carrier, the compressed fluid functioning both to move the carrier to bring the gun into and out of operative position and to operate the gun itself. To make the compressed fluid available for operation of the gun itself I provide fluid connections from the carrier to the gun. The gun is desirably pivotally mounted on the carrier and the fluid connections between the fluid pressure system on the carrier and the gun preferably include a swivel connection coaxial with the pivotal connection between the gun and carrier so that fluid under pressure may be delivered from the fluid pressure system on the carrier to the pivotally mounted gun without interfering with pivoting of the gun on the carrier and without the necessity of employing flexible hoses or the like.

The fluid pressure system on the carrier may include two fluid pumps arranged so that one of them compresses fluid employed for moving the carrier to dispose the gun in operative position and to withdraw the gun therefrom and the other compresses fluid for operating the gun to plug the hole. Connections are also preferably provided so that fluid compressed by both pumps is available to operate the gun in plugging the hole.

Other details, objects and advantages of the invention will become apparent as the following description of certain present preferred embodiments thereof proceeds.

In the accompanying drawings I have shown certain present preferred embodiments of the invention, in which

Figure 1 is an elevational view of a mud gun with its mounting and operating mechanism, the gun shown in this figure being what is known in the art as a pedestal mounted gun and being shown in operative position ready to plug a hole;

Figure 2 is a plan view of the pedestal mounted gun with its mounting and operating mechanism as shown in Figure 1;

Figure 3 is a view similar to Figure 2 but showing the gun in withdrawn or inoperative position, this being the position in which the gun is ordinarily disposed while it is being loaded with clay or while other work is being done on it;

Figures 4, 5 and 6 are elevational diagrams showing the fluid pressure piping and connections for the pedestal mounted gun of Figures 1, 2 and 3;

Figure 7 is a similar plan diagram;

Figure 8 is a view similar to Figure 1 showing a column mounted gun;

Figure 9 is a view similar to Figure 2 of the column mounted gun; and

Figure 10 is a cross-sectional view through the check valve employed between the two pumps in the form of structure shown.

Referring now more particularly to the drawings, the pedestal mounted gun of the form of structure shown in Figures 1 to 7, inclusive, is designated generally by reference numeral 2, being mounted on a pedestal designated generally by reference numeral 3. The gun proper may be of any desired or known construction, and since the details of the gun itself do not constitute the present invention they are not shown. It is sufficient to point out that the gun comprises a cylindrical clay barrel 4 into which clay is charged through a charging opening 5, the clay being

pushed out of the gun through a nozzle 6 by a piston operating in the barrel 4. The piston has a piston rod which extends rearwardly therefrom, or toward the right viewing Figures 1 and 2, and carries a second piston disposed within a cylinder 1 in tandem with the clay barrel 4. The piston in the clay barrel is operated by the piston in the cylinder 1, which latter piston is moved by hydraulic fluid under pressure supplied from a fluid pressure system carried by the gun carrier as will presently be described, the piston rod extending between the pistons in the clay barrel 4 and the cylinder 1 being, of course, suitably packed as well known in the art. The piping for the fluid is not shown in Figures 1, 2 and 3 in order to avoid obscuring other mechanism shown in those figures. The piping is fully shown in Figures 4 to 7, inclusive, and its application to the mechanism of Figures 1, 2 and 3 will be clear upon comparison of Figures 1, 2 and 3, on the one hand, and Figures 4 to 7, inclusive, on the other hand. So far as concerns the basic function of the mud gun in expelling clay through the nozzle 6 thereof to plug a hole, this function is performed in the same manner as well known in the art but through the agency of improved operating and motive means as above referred to and as now to be explained in detail.

The pedestal 3 comprises a base 8 and an upstanding body portion 9 and is mounted on a foundation whose upper surface may be approximately at floor level or slightly above floor level. When the gun is in operative position as shown in Figures 1 and 2 it is tilted with its nose downward, but when it is in inoperative position as shown in Figure 3 it lies approximately parallel to the floor. The mud gun and mounting and operating mechanism shown in Figures 1, 2 and 3 are specifically designed for plugging the tapping hole of a blast furnace. As is well known, the tapping hole of a blast furnace is disposed somewhat below floor level so that the molten metal flowing out will be delivered directly into a trough whence it passes to runners. When the mud gun is in operative position, i. e., the position in which it is shown in Figures 1 and 2, it is disposed largely or partly within the trough in front of the tapping hole so the nose of the gun will be somewhat below floor level as indicated and with the nozzle 6 substantially coaxial with and entering the tapping hole (not shown).

The pedestal 3 is fixedly mounted but carries a sleeve 10 coaxial with the pedestal body 9 and which is rotatable thereon. Connected with the sleeve 10 and in effect integral therewith is an arm 11 which projects radially outwardly from the pedestal and substantially parallel with the floor. The mud gun 2 is suspended from the outer end of the arm 11 and is turnable relatively to the arm both about a vertical axis 12 (Fig. 2) and about a horizontal axis 13 (Fig. 1). The sleeve 10 and arm 11 taken as a unit constitute the gun carrier which is turnable about the pedestal.

Fixed to the pedestal body 9 above the rotatable sleeve 10 and non-rotatable with respect to the pedestal body is a pinion 14 which is coaxial with the pedestal. A bracket 15 is carried by the arm 11 and in turn carries a cylinder 16. A piston operates within the cylinder 16 and has connected therewith a piston rod 17 which has fastened to its outer end a rack 18 which meshes with the pinion 14. The rack 18 is maintained in mesh with the pinion 14 by a collar 19 rotatably disposed about the pedestal and having rollers 20

bearing against the back of the rack 18, the collar 19 thus positioning the rack so as to maintain it in mesh with the pinion in any relative position of the rack and pinion.

When the piston in the cylinder 16 is moved generally downwardly viewing Figure 2 the rack 18 tends to turn the pinion 19 in the clockwise direction about the axis of the pedestal, but since the carrier is turnable about the pedestal while the pinion is not, the result of this movement of the rack is that the carrier turns about the pedestal in the counter-clockwise direction viewing Figure 2 to the inoperative position of Figure 3. Thus by a very simple and effective mechanism which is far less complicated and costly than other mechanisms heretofore provided for swinging gun carriers about their supports I provide for effectively and economically moving the gun carrier so as to dispose the gun in operative position and withdraw the gun from that position.

Fixedly carried by the pedestal is a bracket 21 to which is pivoted at 22 a link 23 pivoted at 24 to a bracket 25 which is mounted so as to rotate with the gun 2 about the vertical axis 12. The effect of the link 23 is to change the angle between the arm 11 and a central vertical plane passing through the gun upon turning of the gun carrier about the pedestal, as will be seen upon comparison of Figures 2 and 3. This is a provision commonly made in the art.

Fixedly carried by the pedestal is a cam 26. Pivotied to the arm 11 at 27 is a lever 28 having at one end a cam following roller 29 which at all times lies against and follows the cam 26. A chain 30 is connected at 31 with the opposite end of the lever 28 and passes about a sheave 32 and is connected with the gun through a bracket 33 carried by the cylinder 7. The sheave 32 is journaled at 34 to a ring 35 disposed about a hook 36 carried by the gun carrier. As the gun carrier turns about the pedestal the follower 29 follows the cam 26 and through the chain 30 alters the angularity of the gun about the axis 13. This also is a provision commonly made in the art. The joint effect of the link 23 and the chain 30, lever 28 and cam 26 is to cause the gun upon being withdrawn from operative position to initially move almost straight back from the hole even though the carrier is turning about the pedestal and, as the gun is further withdrawn, to raise its nozzle so as to bring the gun into more or less horizontal position.

The gun carrier carries a support 37 upon which is mounted an electric motor 38 which drives two fluid pumps 39 and 40, the motor shaft being connected with the pump 39 through a flexible coupling 41 and with the pump 40 through a flexible coupling 42. The carrier also carries a reservoir 43 for fluid adapted to be compressed by the pumps 39 and 40, which fluid will for convenience hereinafter be referred to as oil, although it will be understood that any suitable hydraulic fluid may be employed. A suction line 44 delivers oil from the reservoir 43 to the pump 39. A suction line 45 delivers oil from the reservoir 43 to the pump 40. The high pressure sides of the respective pumps are connected by a pipe 46 containing a check valve 47 arranged so that oil under pressure delivered by the pump 39 can pass the check valve from top to bottom viewing Figure 7 but oil under pressure delivered by the pump 40 cannot pass the check valve from bottom to top viewing that figure.

I provide two valves which may be of any suit-

able or well known construction and operated in any desired manner, as for example, by solenoids; one such is shown in Figure 2 of my Patent No. 1,288,496. One of the valves (for controlling operation of the piston in the cylinder 16) is carried by the carrier and is designated by reference numeral 48 and the other (for controlling operation of the piston in the cylinder 7) is carried by the gun and is designated by reference numeral 49. The valves receive oil under pressure from one or both of the pumps and each valve delivers oil as desired to either end of a cylinder, the oil at the opposite end of the cylinder simultaneously passing back through the valve to the oil reservoir. A pipe 50 delivers oil under pressure from the pump 39 to the valve 48. The oil thus delivered to the valve may pass either through a pipe 51 to the outer end of the cylinder 16 or through a pipe 52 to the inner end of that cylinder, depending on the position of the valve. When oil is passing to the cylinder 16 through one of the pipes 51 and 52 oil from the opposite end of the cylinder is returned to the valve through the other of those pipes and thence back to the reservoir 43 through a pipe 53. Thus by manipulation of the valve 48 oil under pressure delivered by the pump 39 moves the piston in the cylinder 16 in either desired direction to turn the gun carrier about the pedestal.

A pipe 54 delivers oil under pressure from both of the pumps 39 and 40 (since the check valve 47 permits oil under pressure from the pump 39 to flow past it) to a swivel connection 55 coaxial with the axis 12 whereby oil under pressure is delivered to the gun regardless of the angular position of the gun relatively to the carrier about that axis. From the swivel connection 55 the oil passes through a pipe 56 to a swivel connection 57 coaxial with the axis 13 whereby oil under pressure is delivered to the gun regardless of the angular position of the gun relatively to the carrier about that axis. From the swivel connection 57 the oil passes through a pipe 58 to the valve 49 which, as above stated, is mounted on the gun itself. The oil thus delivered to the valve 49 may pass either through a pipe 59 to the outer end of the cylinder 7 or through a pipe 60 to the inner end of that cylinder, depending on the position of the valve. When oil is passing to the cylinder 7 through one of the pipes 59 and 60 oil from the opposite end of the cylinder is returned to the valve through the other of those pipes and thence back to the reservoir 43 through pipes 61, 62 and 63. These pipes are suitably swivel-connected to provide for delivery of the oil from the valve 49 to the reservoir 53 in any angular position of the gun about the axes 12 and 13.

In all of Figures 1, 2 and 4 to 7, inclusive, the gun is shown in operative position. In Figures 4 to 7, inclusive, valves are in the positions they occupy for swinging the gun into the hole and discharging the clay from the gun to plug the hole. In those figures the pressure lines are shown as plain pipes, the return pipes are shown with chain lines along their center lines and the suction pipes through which the oil is drawn from the reservoir to the pumps are shown with dotted lines along their center lines. With the parts as shown oil under pressure is delivered by the pump 39 through the pipes 46 and 50. The oil passing through the pipe 50 enters the valve 48 and passes through the pipe 51 to the outer end of the cylinder 16. Oil from the inner end of the cylinder 16 returns through the pipe 52 to the valve 48 and thence is discharged into the reservoir.

through the pipe 53. Oil compressed by both of the pumps 39 and 40 passes through the pipes 54, 56 and 58 into the valve 49 and thence through the pipe 59 to the outer end of the cylinder 1. At the same time oil is returned through the pipe 60 to the valve 49 and thence through the pipes 61, 62 and 63 to the reservoir.

When the valves 48 and 49 are moved to their opposite positions the pipes now shown as containing fluid under pressure will become the return lines and the pipes between the valves and cylinders now shown as return lines will become pressure lines. The valves are of course individually operable so that either valve may be operated without operating the other. Each valve 10 may be moved to a neutral position when desired so that no oil passes through it from or to any of the connecting pipes. As above stated, the valves are solenoid operated and electrical connections for operating each valve extend from the gun mounting and operating mechanism to the control panel (not shown). Also, wires feeding current to the motor 38 extend to the control panel.

Ordinarily oil passes through only one of the valves 48 and 49 at a time. This is because there is seldom, if ever, any occasion for both swinging the gun about its support and operating the gun to discharge clay therefrom at the same time. In normal operation the gun is swung into the hole and the valve 48 then moved to neutral position, after which the valve 49 is operated to discharge clay from the gun nozzle into the hole. After the clay has been discharged the valve 49 is moved to neutral position. The gun may be left in the hole as long as desired and when it is desired to swing the gun back away from the hole to inoperative position as shown in Figure 3 the valve 48 is operated to accomplish this, the valve 49 remaining in neutral position. From this it will be seen that operation of the valves 48 and 49 so that oil passes through both thereof simultaneously would be an unusual or abnormal operation and in normal procedure oil passes through only one of the valves at a time. This explanation is made because in the above detailed description of the operation of the valves oil is described as passing through both thereof.

Figures 8 and 9 are for the purpose of illustrating one way in which the invention may be applied to mounting and operating mechanism for column mounted guns. In these figures a mud gun 2' is shown as mounted upon a column 64, which column is shown as tilted or disposed at a small angle to the vertical as is the case with some blast furnace supporting columns. The gun may, of course, be supported from a vertical column.

Fastened to the column 64 by straps 65 is a bracket 66 which carries a vertical post 67 which functions to all intents and purposes as does the pedestal of the form of structure shown in Figures 1 to 7, inclusive. The gun is mounted upon and turned about the post 67 by mechanism which is to all intents and purposes the same as the mounting and operating mechanism for the pedestal mounted gun as shown in Figures 1 to 7, inclusive. Parts of the structure of Figures 8 and 9 corresponding to parts of the structure of Figures 1 to 7, inclusive, are shown with corresponding reference numerals each with a prime affixed.

While the gun shown in Figures 8 and 9 is illustrated as being mounted upon a cylindrical column, it may be mounted on a column of any

other shape or upon any suitable support. The invention is equally applicable to guns mounted on pedestals and those mounted on columns and all other suitable supports.

In Figure 10 is shown the check valve 47. It consists of a valve casing 68 within which is a horizontally arranged valve seat 69, the casing having opposed passages 70 and 71 for connection with the oil lines which deliver oil to and away from the check valve. The valve proper or piston is designated 72, being adapted to seat upon the seat 69 through the action of gravity, although it may be spring pressed if desired. The valve provides for free flow therethrough from left to right viewing Figure 10 but closes when there is a tendency for flow in the opposite direction. Oil under pressure passing into the valve casing 68 through the passage 70 raises the piston 72 from its seat and the piston remains raised to permit free flow of oil therewith so long as the oil is flowing from left to right. When flow ceases the valve closes and any tendency of oil to flow from right to left will not unseat the piston.

In Figure 10 the piston 72 is shown as having two passages 73 and 74 drilled therewith at right angles and communicating with each other so as to form a bypass enabling a restricted flow of oil through the valve from right to left even when closed, i. e., in the position shown in Figure 10. The provision of the passages 73 and 74 is optional. In the above description of the operation of my mechanism it has been assumed that no such passages are provided in the check valve. 35 However, it may be desired to swing the gun into and out of position somewhat more quickly than this will be accomplished with the mechanism described above and with pumps of given capacity. This can be accomplished by providing 40 passages such as the passages 73 and 74 in the piston of the check valve so that a limited quantity of oil may bypass the check valve in the upward direction viewing Figure 7 or from right to left viewing Figure 10. Thus the pump 40 will 45 to a limited extent supplement the pump 39 and to that extent the speed of swinging of the gun into and out of position will be increased. The extent of increase of such speed may be determined by the size of the passages provided in the check valve. The larger the passages the faster 50 will be the movement of the gun into and out of position.

While I have shown and described certain present preferred embodiments of the invention it is to be distinctly understood that the invention is not limited thereto but may be otherwise variously embodied within the scope of the following claims.

I claim:

- 60 Mounting and operating mechanism for a mud gun comprising a support, a gun carrier supported by and movable relatively to the support to dispose a mud gun carried by the carrier in operative position relatively to a hole to be plugged and to withdraw the gun therefrom, a fluid pressure system carried by the carrier and means including connections with the fluid pressure system for moving by the compressed fluid the carrier relatively to the support.
- 65 2. Mounting and operating mechanism for a mud gun comprising a support, a gun carrier supported by and movable relatively to the support to dispose a mud gun carried by the carrier in operative position relatively to a hole to be 70 plugged and to withdraw the gun therefrom, a fluid pressure system carried by the carrier and means including connections with the fluid pressure system for moving by the compressed fluid the carrier relatively to the support.
- 75 2. Mounting and operating mechanism for a mud gun comprising a support, a gun carrier supported by and movable relatively to the support to dispose a mud gun carried by the carrier in operative position relatively to a hole to be 75 plugged and to withdraw the gun therefrom, a

fluid pressure system carried by the carrier and means including connections with the fluid pressure system for moving by the compressed fluid the carrier relatively to the support and operating by the compressed fluid the mud gun to plug the hole.

3. Mounting and operating mechanism for a mud gun comprising a support, a gun carrier supported by and movable relatively to the support to dispose a mud gun carried by the carrier in operative position relatively to a hole to be plugged and to withdraw the gun therefrom, a fluid reservoir carried by the carrier, fluid pump means carried by the carrier, connections between the reservoir and pump means providing for compression by the pump means of fluid from the reservoir and means operated by the compressed fluid for moving the carrier relatively to the support.

4. Mounting and operating mechanism for a mud gun comprising a support, a gun carrier supported by and movable relatively to the support to dispose a mud gun carried by the carrier in operative position relatively to a hole to be plugged and to withdraw the gun therefrom, a fluid reservoir carried by the carrier, fluid pump means carried by the carrier, connections between the reservoir and pump means providing for compression by the pump means of fluid from the reservoir and means operated by the compressed fluid for moving the carrier relatively to the support and operating the mud gun to plug the hole.

5. Mounting and operating mechanism for a mud gun comprising a support, a gun carrier supported by and movable relatively to the support to dispose a mud gun carried by the carrier in operative position relatively to a hole to be plugged and to withdraw the gun therefrom and rack and pinion means for moving the carrier relatively to the support.

6. Mounting and operating mechanism for a mud gun comprising a support, a gun carrier supported by and turnable about the support to dispose a mud gun carried by the carrier in operative position relatively to a hole to be plugged and to withdraw the gun therefrom and rack and pinion means for turning the carrier about the support.

7. Mounting and operating mechanism for a mud gun comprising a support, a gun carrier supported by and turnable about the support to dispose a mud gun carried by the carrier in operative position relatively to a hole to be plugged and to withdraw the gun therefrom, a pinion carried by the support, a rack carried by the carrier and meshing with the pinion and means for relatively moving the rack and pinion to turn the carrier about the support.

8. Mounting and operating mechanism for a mud gun comprising a support, a gun carrier supported by and turnable about the support to dispose a mud gun carried by the carrier in operative position relatively to a hole to be plugged and to withdraw the gun therefrom, a pinion fixed to the support, a rack carried by the carrier and meshing with the pinion and means for moving the rack relatively to the pinion to turn the carrier about the support.

9. Mounting and operating mechanism for a mud gun comprising a support, a gun carrier supported by and movable relatively to the support to dispose a mud gun carried by the carrier in operative position relatively to a hole to be plugged and to withdraw the gun therefrom, a

fluid pressure system carried by the carrier and means including connections with the fluid pressure system for moving by the compressed fluid the carrier relatively to the support, said means also including rack means connected with one of the carrier and support and pinion means meshing with the rack means and connected with the other thereof.

10. Mounting and operating mechanism for a mud gun comprising a support, a gun carrier supported by and movable relatively to the support to dispose a mud gun carried by the carrier in operative position relatively to a hole to be plugged and to withdraw the gun therefrom, a cylinder carried by one of the carrier and support, a piston in the cylinder, a rack connected with the piston to be operated thereby and a pinion on the other of the carrier and support with which the rack meshes whereby upon operation of the piston in the cylinder the carrier is moved relatively to the support.

11. Mounting and operating mechanism for a mud gun comprising a support, a gun carrier supported by and turnable about the support to dispose a mud gun carried by the carrier in operative position relatively to a hole to be plugged and to withdraw the gun therefrom, a cylinder carried by the carrier, a piston in the cylinder, a rack connected with the piston to be operated thereby and a pinion on the support with which the rack meshes whereby upon operation of the piston in the cylinder the carrier is turned relatively to the support.

12. Mounting and operating mechanism for a mud gun comprising a support, a gun carrier supported by and turnable about the support to dispose a mud gun carried by the carrier in operative position relatively to a hole to be plugged and to withdraw the gun therefrom, a cylinder carried by the carrier and having its axis disposed generally parallel to the plane of turning movement of the carrier about the support, a piston in the cylinder, a rack connected with the piston to be operated thereby and a pinion on the support with which the rack meshes, the axis of the pinion being disposed generally normal to said plane, whereby upon operation of the piston in the cylinder the carrier is turned relatively to the support.

13. Mounting and operating mechanism for a mud gun comprising a support, a gun carrier supported by and turnable about the support to dispose a mud gun carried by the carrier in operative position relatively to a hole to be plugged and to withdraw the gun therefrom, a pinion fixed to the support and coaxial therewith, a rack meshing with the pinion, and means carried by the carrier and connected with the rack for moving the rack relatively to the pinion to turn the carrier about the support.

14. Mounting and operating mechanism for a mud gun comprising a support, a gun carrier supported by and turnable about the support to dispose a mud gun carried by the carrier in operative position relatively to a hole to be plugged and to withdraw the gun therefrom, a pinion fixed to the support and coaxial therewith, a rack meshing with the pinion, means coaxial with the pinion but rotatable relatively thereto for maintaining the rack in mesh with the pinion in any relative position thereof and means carried by the carrier and connected with the rack for moving the rack relatively to the pinion to turn the carrier about the support.

15. Mounting and operating mechanism for a

mud gun comprising a support, a gun carrier supported by and turnable about the support to dispose a mud gun carried by the carrier in operative position relatively to a hole to be plugged and to withdraw the gun therefrom, a pinion fixed to the support and coaxial therewith, a cylinder carried by the carrier and having its axis disposed in a plane normal to the axis of the support, a piston in the cylinder and a rack connected with the piston to be operated thereby and meshing with the pinion whereby upon operation of the piston in the cylinder the carrier is turned relatively to the support.

16. Mounting and operating mechanism for a mud gun comprising a support, a gun carrier supported by and turnable about the support to dispose a mud gun carried by the carrier in operative position relatively to a hole to be plugged and to withdraw the gun therefrom, a pinion fixed to the support and coaxial therewith, a fluid pressure system carried by the carrier, a cylinder carried by the carrier and having its axis disposed in a plane normal to the axis of the support, connections from the fluid pressure system to the cylinder, a piston in the cylinder and a rack connected with the piston to be operated thereby and meshing with the pinion whereby upon operation of the piston in the cylinder by the compressed fluid of the fluid pressure system carried by the carrier the carrier is turned relatively to the support.

17. Mounting and operating mechanism for a mud gun comprising a support, a gun carrier supported by and turnable about the support to dispose a mud gun carried by the carrier in operative position relatively to a hole to be plugged and to withdraw the gun therefrom, rack and pinion means for turning the carrier about the support and means connected with the support and operable upon turning of the carrier about the support by the rack, and pinion means for turning the gun relatively to the carrier.

18. Mounting and operating mechanism for a mud gun comprising a support, a gun carrier supported by and turnable about the support to dispose a mud gun carried by the carrier in operative position relatively to a hole to be plugged and to withdraw the gun therefrom, rack and pinion means for turning the carrier about the support and means connected with the support and operable upon turning of the carrier about the support by the rack, and pinion means for turning the gun relatively to the carrier both parallel to the plane of turning of the carrier and transversely of that plane.

19. Mounting and operating mechanism for a mud gun comprising a support, a gun carrier supported by and movable relatively to the support to dispose a mud gun carried by the carrier in operative position relatively to a hole to be plugged and to withdraw the gun therefrom, a fluid pressure system carried by the carrier, a cylinder carried by the carrier, a piston therein, mechanical connections between the piston and the support, fluid connections between the fluid pressure system and the cylinder for operating the piston to move the carrier relatively to the support, a second cylinder and piston for operating the gun to plug the hole and fluid connections between the fluid pressure system and the second cylinder.

20. Mounting and operating mechanism for a mud gun comprising a support, a gun carrier supported by and movable relatively to the support to dispose a mud gun carried by the carrier in

operative position relatively to a hole to be plugged and to withdraw the gun therefrom, a fluid pressure system including a pump carried by the carrier, the gun carried by the carrier being movable with respect to the pump, and fluid connections between the pump on the carrier and the gun through which the gun is operated to plug the hole.

21. Mounting and operating mechanism for a mud gun comprising a support, a gun carrier supported by and movable relatively to the support to dispose a mud gun carried by the carrier in operative position relatively to a hole to be plugged and to withdraw the gun therefrom, a fluid pressure system including a pump fixed to the carrier, the gun being pivotally mounted on the carrier, and fluid connections between the pump on the carrier and the gun through which the gun is operated to plug the hole, said connections including a portion coaxial with the pivotal connection between the gun and the carrier so that fluid under pressure may be delivered from the pump on the carrier to the pivotally mounted gun.

22. Mounting and operating mechanism for a mud gun comprising a support, a gun carrier supported by and movable relatively to the support to dispose a mud gun carried by the carrier in operative position relatively to a hole to be plugged and to withdraw the gun therefrom, means for moving the carrier relatively to the support, means for operating the gun to plug the hole, a fluid pressure system carried by the carrier, and connections between the fluid pressure system and each of said means whereby the carrier is fluid pressure operated in its movements relatively to the support and the gun is fluid pressure operated in plugging the hole.

23. Mounting and operating mechanism for a mud gun comprising a support, a gun carrier supported by and movable relatively to the support to dispose a mud gun carried by the carrier in operative position relatively to a hole to be plugged and to withdraw the gun therefrom, a fluid reservoir carried by the carrier, two fluid pumps carried by the carrier, connections between the reservoir and the pumps providing for compression by the pumps of fluid from the reservoir, means for moving the carrier relatively to the support, means for operating the gun to plug the hole, fluid connections between one of said pumps and said first mentioned means whereby the carrier is fluid pressure operated in its movements relatively to the support and fluid connections between the other pump and said second mentioned means whereby the gun is fluid pressure operated in plugging the hole.

24. Mounting and operating mechanism for a mud gun comprising a support, a gun carrier supported by and movable relatively to the support to dispose a mud gun carried by the carrier in operative position relatively to a hole to be plugged and to withdraw the gun therefrom, a fluid reservoir carried by the carrier, two fluid pumps carried by the carrier, connections between the reservoir and the pumps providing for compression by the pumps of fluid from the reservoir, means for moving the carrier relatively to the support, means for operating the gun to plug the hole, fluid connections between one of said pumps and said first mentioned means whereby the carrier is fluid pressure operated in its movements relatively to the support and fluid connections between both of said pumps and said second mentioned means whereby the gun is fluid pressure operated in plugging the hole.

operated in plugging the hole but with fluid compressed by both pumps.

25. Mounting and operating mechanism for a mud gun comprising a support, a gun carrier supported by and movable relatively to the support to dispose a mud gun carried by the carrier in operative position relatively to a hole to be plugged and to withdraw the gun therefrom, a fluid reservoir carried by the carrier, two fluid pumps carried by the carrier, connections between the reservoir and the pumps providing for compression by the pumps of fluid from the reservoir, means for moving the carrier relatively to the support, means for operating the gun to plug the hole, fluid connections between one of said pumps and said first mentioned means whereby the carrier is fluid pressure operated in its movements relatively to the support, other fluid connections between the other pump and said second mentioned means and further fluid connections between said first mentioned pump and said second mentioned fluid connections whereby the gun is fluid pressure operated in plugging the hole but with fluid compressed by both pumps.

26. Mounting and operating mechanism for a mud gun comprising a support, a gun carrier supported by and movable relatively to the support to dispose a mud gun carried by the carrier in operative position relatively to a hole to be plugged and to withdraw the gun therefrom, a fluid reservoir carried by the carrier, two fluid pumps carried by the carrier, connections between the reservoir and the pumps providing for compression by the pumps of fluid from the reservoir, means for moving the carrier relatively to the support, means for operating the gun to plug the hole, fluid connections between one of said pumps and said first mentioned means whereby the carrier is fluid pressure operated in its movements relatively to the support, other fluid connections between the other pump and said second mentioned means, further fluid connections between said first mentioned pump and said second mentioned fluid connections whereby the gun is fluid pressure operated in plugging the hole but with fluid compressed by both pumps and a check valve in said last mentioned fluid connections to prevent fluid compressed by said second mentioned pump from moving toward said first mentioned connection.

27. Mounting and operating mechanism for a mud gun comprising a support, a gun carrier supported by and movable relatively to the sup-

port to dispose a mud gun carried by the carrier in operative position relatively to a hole to be plugged and to withdraw the gun therefrom, a fluid reservoir carried by the carrier, two fluid pumps carried by the carrier, connections between the reservoir and the pumps providing for compression by the pumps of fluid from the reservoir, means for moving the carrier relatively to the support, means for operating the gun to plug the hole, fluid connections between both of said pumps and said first mentioned means whereby the carrier is fluid pressure operated in its movements relatively to the support, said connections including a restricted fluid passageway for limiting the effect of one of said pumps in movement of the carrier relatively to the support, and free fluid connections between both of said pumps and said second mentioned means whereby the gun is fluid pressure operated in plugging the hole.

28. Mounting and operating mechanism for a mud gun comprising a support, a gun carrier supported by and movable relatively to the support to dispose a mud gun carried by the carrier in operative position relatively to a hole to be plugged and to withdraw the gun therefrom, a fluid reservoir carried by the carrier, two fluid pumps carried by the carrier, connections between the reservoir and the pumps providing for compression by the pumps of fluid from the reservoir, means for moving the carrier relatively to the support, means for operating the gun to plug the hole, fluid connections between one of said pumps and said first mentioned means whereby the carrier is fluid pressure operated in its movements relatively to the support, other fluid connections between the other pump and said second mentioned means whereby the gun is fluid pressure operated in plugging the hole, further fluid connections between said pumps whereby the gun is fluid pressure operated in plugging the hole with fluid compressed by said first mentioned pump as well as by said second mentioned pump, a check valve in said last mentioned fluid connections to restrict the flow of fluid compressed by said second mentioned pump toward said first mentioned pump, and a restricted bypass permitting a predetermined relatively small quantity of fluid to flow past the check valve from said second mentioned pump toward said first mentioned pump to assist in moving the gun relatively to the support.
